IDENTIFICATION CARD SYSTEM
Lawrence H. Kellen, Rte. 5, Le Mars, Iowa 51031
Filed Nov. 20, 1964, Ser. No. 412,738
1 Claim. (Cl. 317—134)

My invention relates to an identification card system. An object of my invention is to provide an identification card system in which the identification of the proper person will be relatively positive.

A further object of my invention is to provide an arrangement in association with the identification card system wherein the arrangement will not print a bill or invoice unless the card fulfills the precise requirements of identification.

A further object of my invention is to provide an arrangement which can be altered as desired to change the identifying requirements.

A further object of my invention is to provide an identification card system which will operate only under the proper conditions and which will be especially useful in service stations or the like.

With these and other objects in view, my invention consists in the construction, arrangement, and combination of the various parts of my device, whereby the objects contemplated are attained, as hereinafter more fully set forth, pointed out in my claim, and illustrated in the accompanying drawings, in which:

FIGURE 1 is a plan view of the device,

FIGURE 2 is a side elevation of FIGURE 1 with fragmentary sections, and

FIGURE 3 is a schematic view of the electrical circuit used in the device.

My invention contemplates the provision of a device and card arrangement wherein a card which may be fraudulently used by a person other than the proper person will prevent operation of the device and will similarly inform the operator that the card used was obtained fraudulently or was lost by the proper owner of the card and is being used by someone else, etc. The arrangement is especially useful for service station uses where purchases of gasoline and the like are being made.

In describing my invention the character 10 designates a flat plastic card or other material which will contain the name of the proper owner as well as the raised numbers 11 to be printed on the invoice, and the character 12 indicates a series of spaced openings provided in the card, which openings will correspond numerically to four numbers for instance which will be the numbers used by the original owner of the card, and these numbers preferably can be the four last numbers of his or her Social Security number so that the numbers will be readily remembered by the owner of the card, and which numbers will not appear on the card itself.

The character 13 indicates a series of electric solenoids having the plungers 14 therein, these solenoids serving to draw the plungers to the maximum upper position shown in FIGURE 2 if the respective plungers are not blocked or restricted by the unpunched portions of the card itself. The solenoids will be numbered 1, 8, 2, 6, 0, 4, 3, 7, 9, and 5 as shown by the corresponding characters, however the positioning of these solenoids can be changed when desired, and each solenoid is connected as shown by the wiring diagram FIGURE 3 to the respective switches 15 which switches have the number values from 1 to 0 placed thereon as shown, these switches being of the type which will close the circuits when the switches are pressed downwardly and when pressed again will open the circuit.

Each card 10 will also include a pair of openings at 16 which are adapted to receive the circular pegs 17, the

2

pegs 17 being secured in the cavity portion 18 in which the card will be held when being tested, it being noted that the portion 18 is wider than the card itself so that the space between the pegs 17 and the openings 12 can be varied at the central office when desired to change the arrangement so that the proper card will fit the proper unit.

The character 18a designates a covering plate hinged at 18b to the casing 49, the character 18c designating flanges attached to the plate 18b.

FIGURE 3 illustrates the same switches and solenoids as well as the plungers for each part of the circuit, and the solenoids will also carry the contact bars 19 suitably insulated from the plungers.

The characters 20a indicates contacts, the character 21a indicating further contacts which are bridged by the contact bars 19.

The character 23 indicates a further solenoid which operates a plunger 24 (see FIGURE 2) which plunger 24 includes a locking extension 25 adapted to be received within a keyway or slot 26 provided in the shaft 27. The character 23a indicates a switch.

The shaft 27 is securely attached to a casing 28 (see FIGURE 2), the casing 28 including the roller or printing mechanism which is more or less conventional in such constructions, the character 29 indicating a handle pivoted at 30, the handle 29 being formed integrally with the arm 31 which is pivoted at 32 to a substantially U-shaped yoke 33 to which yoke is journaled a roller 34. Journalled at 35 to the levers 36, which are pivoted at 37 to a casing wall 38, is a suitably inked roller 39.

Attached to the member 33 at 40 is a spring 41 which is attached at 42 to the casing wall 43, the characters 44 and 45 indicating further casing walls, the handle 29 operating within a slot 46.

The device operates in the following manner.

Assuming that an owner of a card 10 is using the card for purchasing gasoline at a service station for instance, the operator of the service station will place the card 10 in the cavity 18 and so that the openings 16 receive the pegs 17. The plate 18a is then swung over to cover the plungers 14 and card 10, the flanges 18c holding the card securely, the hinges 18b being relatively stiff to keep the plate 18a in a flat horizontal position. The switch 23a is then closed. Assuming that the correct numbers as given to the operator contain the numbers 1, 8, 7, and 5 (see FIGURE 1), the operator will then press the corresponding numbers on the switches 15, which accordingly will actuate the proper solenoids as shown by FIGURE 3 whereas the plungers 14 will be pulled upwardly into the solenoids and will project upwardly through the openings 12 in the card 10. This action will accordingly cause the circuit to be applied to the solenoid 23 which will release the plunger 24 and member 25, so that the casing 38 can be operated, the invoice 47 being placed in position on the card. At this point the handle 29 can be pulled over in the direction of the arrow 48 and the various members 31, 33, 36, etc. will operate the inking roller 39 so that the number 11, etc. can be applied to the invoice or bill 47.

However, in case an incorrect number is given and this number is applied to a switch 15, this particular plunger will not pass through the card 10 and the circuit will not be completed, thereby indicating that the card is fraudulent, and the locking member 25 will remain in locked position.

In case a number is repeated more than once in the machine, this will not affect the operation of the same, except that fewer openings 12 will be needed.

The entire device is suitably enclosed within the said casing 49, and if desired the shapes of the pegs 17 can be changed to larger pegs or different shapes if it is desired

to start from a new basis at any time, the spacing of the pegs 17 with respect to the openings 12 determining the proper cards, and which spacings can be altered as explained.

It will now be noted that I have provided the advantages mentioned in the objects of my invention with further advantages being apparent.

Some changes may be made in the construction and arrangement of the parts of my invention without departing from the real spirit and purpose of my invention, and it is my intention to cover by my claim any modified forms of structure or use of mechanical equivalents which may be reasonably included within its scope.

I claim as my invention:

An identification card system comprising a card having indicia thereon, said card having a plurality of predetermined openings, a device including a plurality of plungers adapted to register with certain of said openings, means for actuating said plungers to enter said certain openings, said plunger actuating means including solenoids, switches for controlling said solenoids, said device including a casing including a printing mechanism pivoted to said casing, a circuit controlling said solenoids, said circuit being bro-

ken when one of said plungers will not pass through a corresponding opening, a further solenoid for controlling said printing locking mechanism, a further circuit connected to said further solenoid, said further circuit being open when one of said plungers is inactive, said device including a casing including a recessed portion for receiving said card, pins attached within said recessed portion, said cards having further openings spaced from said openings, changing position of said pins affecting the proper positioning of said openings with respect to said plungers.
